LOW WATER ALARM

Filed Oct. 22, 1924

FIG. 1.

FIG. 2.

FIG. 3.

Inventor

N. M. Barker

John Boyle Jr.

Attorney

UNITED STATES PATENT OFFICE.

NORMAN M. BARKER, OF CLEVELAND, OHIO.

LOW-WATER ALARM.

Application filed October 22, 1924. Serial No. 745,242.

My invention relates to a temperature controlled mechanism and has specifically in view the provision of a low water alarm for locomotive boilers.

5 In my prior Patent No. 1,496,614, issued June 3, 1924, I have disclosed an arrangement utilizing a body of fusible material which will melt at a predetermined water level and thereby cause the operation of an 10 alarm to warn the engineer.

The improvements embodied in the present application are to be used with a device of the character covered by my prior patent. However, some of the improvements are of 15 general application and can be utilized in other types of low water alarms.

One of the objects of the invention is to provide a construction whereby the fusible element or similar heat responsive member 20 can be connected to the crown sheet in such a manner so that it will be substantially insulated therefrom, whereby the heat from combustion can be conducted through the water to a point above the water without 25 substantial heat loss to the water.

Another object is to provide a means to shield the fusible plug-holding element from the cooling effect of the water contained in the moist steam at the surface of the boiling water.

A further object is to provide means for compensating for the different expansion of various parts.

A further object is to provide a locking device for the tool which is used in resetting the device.

A still further object is to provide a valve for testing the alarm in order to see that it is in operative condition.

40 Another object is to provide a valve, the seat of which can be readily reground.

With these and other objects in view, my invention consists of certain novel and peculiar features of construction and combination of parts as will be hereinafter more fully described and particularly pointed out in the claims.

In the drawings:

50 Fig. 1 is a vertical section of the low water alarm in position for use;

Fig. 2 is a detail elevation of the upper end of the alarm; and

Fig. 3 is a fragmentary vertical section of the preferred form of protecting jacket.

55 Referring more particularly to the drawings, 2 is the crown sheet and 1 is the

wrapper sheet of a boiler. Tapped into the wrapper sheet is a stuffing box 3 and tapped into the crown sheet is a shell 4. Passing through the shell 4 and supported thereby is the heat conducting member 5 provided at its upper end with a chamber 6 for holding the fusible metal 7 and at its lower end with a removable cap 8, made of Monel metal, refractory material, or any suitable material for resisting the heat.

The heat conducting member 5 is as completely heat insulated from the shell 4 as it is possible so to do. With this end in view, there is an air space 9 between the two parts and where the shoulder 10 rests on the shell 4, there is provided an asbestos packing ring 11. A similar ring 12 is provided between the said shoulder and the nut 14. The insulation provided by the air space 9 may be sufficient in itself to accomplish the desired result. However, when the asbestos packing rings are used, more complete insulation is had, so that the fusible metal will melt with more water over the 80 crown sheet, than if the packing rings are omitted.

It will be noted that the bottom of the fusible material chamber 6 is above the insulated point of contact, as represented by the flange 10. This arrangement insures that the fusible material 7 will remain solid as long as the water is above the insulated point of contact, since the water acts directly on the exterior of the fusible material chamber 6.

When the water drops below this insulated point of contact, the relatively complete insulation of the shell 4 from the heat conducting member 5 permits a rapid rise in temperature of the fusible material chamber 6, thus melting the fusible material as quickly as possible.

When the water in the boiler drops to a level where it will no longer cool the upper end of the heat conducting member 5, there will be no cooling effect therefrom upon the fusible metal and all the heat which is being put into the member 5 will be transmitted along such member to the fusible metal. Very soon after the water has fallen to the said level, the alarm will operate, and in the particular arrangements shown, while there is still from about one and a half to four and a half inches of water over the 105 crown sheet.

Immediately above the surface of the

water in the boiler, the steam is very moist. This moist steam has practically the same cooling effect as the water in the boiler, and if no protection is afforded to the upper 5 end of the member 5, the moist steam will tend to keep the temperature of the said member sufficiently low to prevent melting of the fusible plug even after the water has dropped below the desired level. In order 10 to avoid this situation, I surround the upper portion of the member 5 with a jacket 15 so that the moist steam, due to the fact that as the bubbles of steam rise to the surface of the water, they burst, thus causing 15 spray, which is very high in cooling quality, will not come in contact with the upper portion of the member 5.

In the form of jacket shown in Fig. 1, the upper and lower ends of the jacket are perforated at 16 to permit water to circulate 20 within the jacket when the jacket is surrounded by water.

In the form shown in Fig. 3, the jacket 15' is made integral with the nut 14 and is 25 open at the top and not perforated at the bottom.

In the form shown in Fig. 1, as soon as the water falls to a level below the perforations 16 in the bottom of shell 15, the fusible 30 metal will melt.

In the form shown in Fig. 3, the fusible metal will melt slowly after the water has dropped below the top of the jacket 15'.

The heat capacity of the member 5 when 35 insulated is so related to the quantity of fusible metal that the alarm will operate while a substantial quantity of water is still over the crown sheet.

The operating plunger 17 is provided on 40 its lower end with a screw thread 18, which is supported by and embedded in the fusible metal 7. Threaded on the upper end of the member 5 is the tube 19 which is in tight but expandible engagement with the stuffing 45 box 3 and which is threaded at its upper end to receive the housing 20. Screwed into the top of the housing is the bushing 21, having an aperture 22 therethrough for the valve rod 23. Screwed onto the nut 21 is 50 the valve casing 24, the inlet port 25 being connected to the steam chamber through the pipe 26 and the outlet port 27 being connected to the whistle 28. The valve seat 29 is threaded in the body of the valve and 55 has an operating handle 30 at its upper end. To test the valve, it is merely necessary to screw the valve seat off of the valve head 23, whereupon steam will pass therethrough, showing the device is in operative condition.

60 It will be noted that the tube 19, housing 20 and valve casing 24 are united into one piece. When heat strikes the same before it does the operating plunger 17, a greater expansion occurs with the result that the 65 valve seat will be lifted off of the valve head,

thereby permitting leakage until later, the plunger is heated to the same temperature as the tube, when it in turn will expand, and after the tube has reached its limit of expansion. To take care of this differential 70 expansion, I interpose a compensating spring 31 between the valve rod 23 and the upper end of the operating plunger 17. With this construction, the valve 23 will always be held firmly against its seat, regardless of difference in expansion of the outside and inside members. 75

The spring 31 also provides a means to assist in regrinding the valve. The valve rod is provided with guides 32 and when 80 it is desired to grind the valve, this can be done by merely turning the handle 30 of the valve seat back and forth against the pressure of the spring 31, the guides preventing rotation of the valve rod. 85

Within the housing 20 is the compression spring 33, which exerts a continuous downward pressure on the operating plunger through the medium of the collar 34.

In operation, when the fusible metal 90 melts, plunger 17 is forced downward by the pressure of the spring 33 thereby moving the valve rod 23 off of the valve seat 29 and permitting steam to pass from the boiler to the alarm whistle. When the temperature of the fusible material is reduced by the water reaching the proper level in the boiler, the fusible material solidifies around the screw-threaded end of the operating plunger. 95

For resetting the operating plunger, it is provided with a squared portion 35, for engagement with a wrench 36. On turning the operating stem, on account of its threaded engagement with the fusible plug, it will be elevated against the pressure of the spring 33 to move the valve stem to closed position and thus shut off the passage of steam from the boiler to the alarm. The aperture in the housing is closed by the collar 37, which is held to the housing by means of a bayonet joint, the lugs 38 passing through an aperture in the shoulder 39 and then being turned to position so as to rest thereon. The wrench 36 passes through an ear 40 on the housing and an ear 41 on the collar 37 and this locks the two against rotation. The end of the wrench is provided with a slot 42 to hold a seal. The wrench cannot be withdrawn without breaking the seal and in this manner a check is kept on whether or not the alarm has operated. 110

What I claim is:

1. In a device of the character described, 125 a heat conducting member, means for supporting said member in the crown sheet of a boiler, a heat responsive device carried by the upper end of the heat conducting member and wholly disposed at a distance above 130

- the crown sheet of the boiler comparable to the predetermined water level at which the device shall operate, the said heat responsive device being in heat conducting relation with 5 the surrounding water, the portion of the heat conducting member below the said responsive device being substantially heat insulated from the surrounding water.
2. In a device of the character described, 10 a shell connected to the crown sheet of a boiler, a heat conducting member arranged in said shell and supported thereby, the said member being substantially heat insulated from the shell, and a heat responsive device carried by the heat conducting member, the said device being located above the insulated portion of the heat conducting member.
3. In a device of the character described, 15 a heat conducting member, a chamber carried by the upper end of the said member, fusible material in the said chamber, the said material adapted to remain solid only as long as water is in contact with the walls 20 of said chamber and means for insulating the heat conducting member from the cooling effect of the water below the said chamber.
4. In a device of the character described a shell connected to the crown sheet of a boiler, a heat conducting member arranged in said shell and supported thereby, the said member being substantially heat insulated 25 from the shell, and a heat responsive device carried by the heat conducting member, the said device being located at a point above the point of contact between the heat conducting member and the shell.
5. In a device of the character described, 30 a shell carried by the crown sheet of a boiler, a heat conducting member located therein, the said member having a shoulder resting on the shell and heat insulating packing between said shoulder and shell.
6. In a device of the character described, 35 a shell carried by the crown sheet of a boiler, a heat conducting member provided with a shoulder resting on the upper end of the shell, heat insulating packing between said shoulder and shell, the heat conducting member being spaced from the shell to provide 40 an insulating air space, and a heat responsive device above the said shoulder.
7. In a device of the character described, 45 a heat conducting member provided with a heat responsive device at its upper end and located above the crown sheet, means for substantially heat-insulating the said member from the crown sheet, and means for 50
- protecting the upper end of the heat conducting member from the cooling effect of moist steam and comprising a jacket surrounding the said heat-conducting member. 60
8. In a device of the character described, a heat conducting member provided with a heat responsive device at its upper end and located above the crown sheet, means for substantially heat insulating the said member from the crown sheet and means for protecting the upper end of the heat conducting member from the cooling effect of moist steam. 65
9. In a device of the character described, a heat conducting member provided with a heat responsive device at its upper end and located above the crown sheet, means for substantially heat insulating the said member from the crown sheet, a nut for securing the heat conducting member in position and a jacket carried by the nut and spaced from the said upper end to protect it from the cooling effect of moist steam. 70
10. In a device of the character described, a body provided with a heat responsive device, a plunger operatively connected therewith and provided with a valve, a tube surrounding the plunger and having a passage provided with a valve seat, and means for normally holding said valve on said seat, said means comprising means for compensating the difference in expansion between the rod and tube. 75
11. In a device of the character described, a body provided with a heat responsive device, a plunger operatively connected therewith and provided with a valve, a tube surrounding the plunger and having a passage provided with a valve seat and means for normally holding said valve on said seat, said means comprising means for compensating the difference in expansion between the rod and tube, and comprising a spring interposed between the valve stem and plunger. 80
12. In a device of the character described, a body provided with a heat responsive device, a valve, a valve seat cooperating with the said valve, the valve being resiliently supported and normally held seated by said heat-responsive device, and means to prevent rotation of the valve as the seat is rotated. 85
13. In a device of the character described, a body provided with a heat responsive device, a plunger operated thereby, to open a valve to permit escape of steam, a valve seat, and means for independently operating the valve by movement of the valve seat. 90

In testimony whereof I affix my signature.
NORMAN M. BARKER.
